219,076

HULL FOR AMPHIBIOUS VEHICLES

Lee Howard Hoffman, 13121 Wilshire,
Detroit, Mich. 48213

Filed May 8, 1969, Ser. No. 17,068

Term of patent 14 years

Int. Cl. D12—06

U.S. Cl. D71—1

FIG. 4

FIG. 5

FIG. 1 is a front and side view of the hull for amphibious vehicles embodying my novel design.

FIG. 2 is a front view thereof.

FIG. 3 is a rear view thereof.

FIG. 4 is a top view thereof.

FIG. 5 is a side view thereof.

The elements shown in broken lines are included for illustrative purposes only.

What I claim is:

The ornamental design of a hull for amphibious vehicles, as shown and described.
